UNITED STATES PATENT OFFICE.

GEORGE WASHINGTON MEYERS, OF RAHWAY, NEW JERSEY, ASSIGNOR TO NATIONAL PNEUMATIC COMPANY, OF NEW YORK, N. Y., A CORPORATION OF WEST VIRGINIA.

SAFETY MECHANISM FOR STREET CAR AND DOOR OPERATION.

Application filed August 20, 1919. Serial No. 318,774.

This invention relates to safety mechanism for street and other railway car and door operation.

The object of the invention is to provide means whereby the doors of a street or other railway car cannot be opened while the car is under headway, whether under power propulsion or coasting.

A further object of the invention is to provide a locking mechanism to prevent operation of the motorman's controller whenever a door of the car is opened.

A further object of the invention is to provide a locking mechanism to prevent the operation of the doors by either the motorman or the conductor as long as the car is under headway.

A further object of the invention is to provide means in a control and locking system of the character referred to which enables temporary operation of the doors for emergency use whether the car is under headway or not.

Further objects of the invention will appear more fully hereinafter.

The invention consists substantially in the construction, combination, location and relative arrangement of parts, all as will be more fully hereinafter set forth as shown in the accompanying drawings and finally pointed out in the appended claims.

Referring to the accompanying drawings:

Fig. 1 is a view in diagram illustrating the circuit arrangement employed in carrying out my invention as applied to the control of the motorman's controller and of the door switches of a street car.

Fig. 2 is a view showing more specifically the centrifugal circuit breaker operated by or from the car propelling motor and a locking device with a relay magnet controlling the circuit of the latter, the circuit of the relay device being controlled by the centrifugal circuit breaker.

Fig. 3 is a view illustrating the application of a lock mechanism employed in connection with my invention as applied to the motorman's door control stand.

Fig. 4 is a top plan view of the construction shown in Figure 3.

Fig. 5 is a view similar to Figure 3 showing the application of a lock device employed in connection with my invention as applied to a conductor's door control stand.

Fig. 6 is a broken view in side elevation showing the construction for securing the conductor's control lock box to its supporting stand.

Fig. 7 is a face view with parts broken out showing a construction of a centrifugally operated circuit breaker employed for controlling the circuit of the relay magnet.

Fig. 8 is a broken detail view in section on the line 8—8 of Figure 7, looking in the direction of the arrows.

Fig. 9 is a view in horizontal section on the line 9—9 of Figure 10, looking in the direction of the arrows.

Fig. 10 is a view in vertical section showing the structure of the lock mechanism employed in connection with my invention.

Fig. 11 is a broken detail view similar to Figure 10 showing somewhat more clearly the structure of the lock mechanism.

Fig. 12 is a broken detail view on the line 12—12 of Figure 2, looking in the direction of the arrows.

Fig. 13 is a detail in part similar to Fig. 11 showing the inclined surface on the king bolt reversed.

The same part is designated by the same reference numeral wherever it occurs throughout the several views.

In the present method of street car operation and door control it is frequently possible for passengers or others to open the car doors while the car is under headway whether from its propelling power or from coasting downgrade. The result is that danger is incurred of accident and injury through the opening of the doors while the car is in motion. It is among the special purposes of my present invention to provide a system of control which,

while permitting opening of the doors temporarily or under emergency conditions, prevents the doors from operating under normal operation so long as the car is under headway. In carrying out my invention I employ lock devices for the control stands through

which the door operations may be controlled by either the motorman or the conductor on the car and I also provide a locking mechanism for the motorman's control stand through which control of the propelling motor is effected. These locking devices are, or

may be, of the same structure and therefore a description of the one will apply equally to all of the locking devices. Each locking device is controlled electrically by devices, the

circuits of which are in turn controlled by a relay magnet. The circuit of the relay magnet is under the control of a centrifugal circuit breaker which is operated whenever and 5 so long as the car is under headway, whether by the propelling motor or otherwise; the essential feature being that so long as the car is under headway the centrifugal circuit breaker prevents the completion of the circuit 10 of the relay magnet through which the circuits of the control locking magnets pass. A convenient and simple arrangement is shown wherein the centrifugal circuit breaker is intended to be operated by a car propelling motor and for this purpose and to illustrate the principles involved, the centrifugal circuit breaker is shown as connected to the motor shaft to be operated whenever the motor shaft is in rotation, whether such rotation is 15 affected by the supply of operating current to the motor or to the gearing which connects the motor shaft to the car axles.

A locking system of the nature referred to is also, in accordance with the principles of 20 my invention, connected up with the door operations in such manner that door controlled switches also control the circuits of the controller lock so that the lock cannot be released until the doors are closed.

25 Referring to the general layout of a lock and control system embodying my invention as illustrated in Figure 1, reference numeral 14 designates the car propelling motor and 30 15 the motor shaft. To the latter is connected a centrifugal circuit breaker device indicated generally by reference numeral 16. The relay magnet which controls the circuits of the lock magnets is indicated at 17, the circuit of said relay magnet being controlled by the 35 40 centrifugal circuit breaker 16 and also when desired for temporary or emergency operation by a push button switch device indicated generally at 18. Reference numeral 19 designates the motorman's propelling motor controller and 20 a lock device therefor. 21 designates a lock device for the door control system which is operable by the motorman. 22 designates the lock device for the conductor's door control stand 23. A car is diagrammatically indicated at 24 having the doors 25 and 45 control switches indicated generally at 26, 27 in circuits which include the magnet of the motorman's propelling control lock. The operation generally, before proceeding with a 50 specific description of the structure, is as follows:—As long as the car has headway a centrifugal circuit breaker 16 maintains the circuit of relay magnet 17 open and as long as the relay magnet 17 is de-energized a switch 55 device 28 controlled thereby remains open. This switch device 28 is included in the current supply connections for all of the locks so that the lock magnets remain de-energized while the circuit is open. This condition 60 obtains as long as the centrifugal circuit

breaker device 16 remains in operation, that is, so long as the car has headway, and consequently the door control devices, whether under the operation of the motorman or of the conductor of the car, remain locked, thereby rendering it impossible for the door to be opened so long as the car is in motion, excepting by the special push button described above. The motor controller lock, on the other hand, because of the reversal of the inclined surface on the king bolt, as described below, remains unlocked while its magnet is de-energized. When, therefore, the car comes to rest, and the centrifugal circuit breaker 16 is permitted to complete the circuit of the relay magnet 17, thereby closing the switch 28, and energizing the magnets of the various door locks, the door control locks may be operated and the doors opened. When the doors are opened, the push disconnectors at 26 and 27 will close the circuit through the controller lock magnet at 20, thereby energizing the same to lock the controller against movement so that the car cannot be started while any of the doors remain open. When, therefore, all the doors are closed, and lock 20 becomes unlocked, controller 19 may be manipulated for normal operation.

55 The push disconnectors 26 and 27 diagrammatically shown in Fig. 1 are normally held closed by the spring arm, but when the doors 25 now shown in open position are closed, they push against the arms of said disconnectors and open the contact points by overcoming the force of the spring arm thereby accomplishing the result just set forth.

100 I will first describe the construction of the centrifugal circuit breaker, particular reference being had to Figures 2, 7, 8 and 12. This breaker includes an annular member 29 composed of complementary sections placed flatwise against each other and suitably bolted together. Upon the opposing faces of these members 30, 31 are formed chambers within which are received rings 32, 33 of suitable insulating material such, for example, as bakelite. On their opposed faces the rings 32, 33 are formed with complementary recesses, preferably spherical in contour, as indicated at 34. Placed within each of the spherical recesses 34 is a ball 35. The rings 32, 33 encompass a ring 36 of insulating material which is formed with a portion or annular rib 37 which separates from each other two conductor rings 39, 40, which latter respectively extend into the spherical recesses 34 a distance sufficient for the balls 35 or some one or more of them to contact therewith when the centrifugal breaker device is standing still. The conductor ring 40 is grounded in any suitable or convenient manner, as for instance, through a connection 38 to the frame of the motor. To the other conductor ring 39 is connected a conductor 41 which is in elec- 115 120 125 130

trical connection in any suitable or convenient manner with the circuit of the relay magnet 17. A simple arrangement is shown wherein a block or spool piece 42 of insulating material and having a longitudinal bore therethrough is mounted upon and centrally of the outer member 30 of the centrifugal circuit breaker, and preferably offset therefrom by means of an insulating or fibre disc 43. Inserted through the bore of the block 42 is a pin 44 (see Figure 12) having a spherical head 45 which projects beyond the outer end of the block 42. The block 42 is provided with a hole or opening therethrough, through which extends a conductor 41 to make electrical contact with the pin 44. The projecting end of the pin 44 receives a boss 46 which is formed with a concave seat in which the ball 45 is seated and is held by means of a cap 47 formed with a co-operating hemispherical recess or seat therein. The boss 46 forms part of a hanger for a dependent weight 48. To the boss 46 is connected one terminal of the circuit connection for relay magnet 17. The other terminal of said relay magnet circuit is connected to a current source such, for example, as a battery indicated at 49 in Figure 1. When the relay magnet 17 is energized its armature actuates a projecting member 50 to bridge the contacts 51, 52, which contacts are included in the current supply connections for all of the lock magnets.

The operation of the centrifugal circuit breaker device is as follows:—Whenever the car is under headway the balls 35 are thrown by centrifugal action radially outwardly so as to be free and clear of contact with the conductor strips or rings 39, 40 and, consequently the circuit of the relay magnet 17 is maintained open as long as the centrifugal circuit breaker is revolving. When, however, the centrifugal circuit breaker comes to rest, that is, when the car loses its headway, one or more of the balls 35 will gravitate into position to close the circuit between the conductor rings 39, 40 at one or more points. These balls in completing the circuit of the relay magnet thereby energize said magnet and operate the switch device 28, causing the bridge member 50 to bridge the space between contacts 51 and 52, thereby completing the current supply circuits of the locking devices.

I will now describe the construction of one of the locking devices, it being understood that the structure of the locking devices is the same whether for the motorman's propelling motor controller or door controller or for the conductor's door controller except that the inclined surface on the king bolt is reversed in the motorman's controller motor lock, as is shown in Fig. 13. In this connection reference is had to Figures 9, 10, 11 and 13. Carried by the controller shaft 53 is a cam wheel or disc indicated at 54 formed in its peripheral edge with a seat or depression 55 adapt-

ed to receive a projection 56 on the end of a king bolt 57. The king bolt 57 is mounted to slide in the lock casing 58 on suitable guides formed in the lock casing. Connected to the king bolt is a cross piece 59, to the ends of which are connected tension springs 60, the other ends of said springs being anchored as at 61 in the casing. The tension of the springs 60 exerted upon the king bolt 57 tends to project the locking end 56 thereof against the peripheral edge of the wheel or disc 54 on the shaft of the controller and into the seat 55 formed therein whenever the seat is in position to receive the same. This position determines the off position of the car propelling motor as well as the off position of the door control shaft with the doors in their closed position. The king bolt 57 is longitudinally slotted both vertically and horizontally and extending transversely through the horizontal slot indicated at 62 is a stud 63 which is fastened at its ends in the casing 58. Pivotally mounted upon the stud 63 is a locking toggle 64. One end of the locking toggle 64 carries a roller 65 as in bearing 65'. The roller is adapted to engage and slide along an inclined surface 66 when the locking toggle moves toward its locking position until the longitudinal centre or axial line of the toggle member 64 passes beyond the inclined surface 66, whereupon the roller 65 will engage the wall 67 of the vertical slot 68 in the king bolt and form a lock for said king bolt, thus preventing the same from being moved towards the left, as seen in Figures 9, 11, 13, that is, preventing said king bolt from being moved from its locking position. In order to normally maintain the locking toggle 64 in locked position for the door locks and in unlocked position for the motor locks, the cross member 59 of the king bolt is formed with an overhanging extension 69 which receives the bearing of a spring 70 and permits it to slide along toggle 64 when the bolt is actuated. The tension of this spring is exerted on the tail end portion of the locking toggle to rock the locking end of the toggle in locking position for the door locks and out of locking position for the motor locks. Extending vertically through the vertical slot 68 in the king bolt is a connection 71 for extension of the armature of the locking magnet 72, the said extension 71 being pinned or otherwise suitably connected to the locking toggle 64. When the magnet 72 is energized, the armature 73 of the magnet is drawn downwardly, thereby pulling the locking end of the locking toggle 64 out of locking position and releasing the king bolt in the door locks, but locking the king bolt in the controller locks. Hence the unlocked king-bolt may be withdrawn from the locking engagement with the disc or wheel 54 on the control shaft when power is applied to said shaft to rotate the wheel 54 therein. The armature 73 of the lock magnet is drawn

downwardly into seating engagement with the core piece 74 of the magnet. In practice I prefer to adjustably mount the core piece 74 so that the residual magnetism of the magnet 5 may be utilized after the circuit of the magnet is opened to retain the armature 73 drawn down or seated for a desirable period of time, depending upon the adjustment of the core 74 to retard or delay the return of 10 the locking toggle towards locking position. For this purpose the core 74 is mounted upon or carried by an adjusting screw 75. A stop screw 76 forms a limited stop to arrest the rocking movement of the locking toggle upwardly so as to bring the longitudinally central axis of the locking toggle from slightly 15 above the lower edge of the vertical locking wall 67, thereby permitting an easy and quick release of the lock instantaneously with the 20 energization of the relay magnet.

In Figures 3, 4, 5 and 6 I have shown the locks 22 and 21 applied to the control stands 23 and 77. It is to be understood, of course, that these locks may be applied and attached 25 to the control stands in any suitable or convenient manner, and, therefore, my invention is not to be limited or restricted in respect to the method of attaching the locking devices to the stands, the essential feature being 30 that the control shafts in said stands shall carry or have carried or otherwise connected thereto the cam wheels or discs indicated at 54 disposed and arranged in co-operative relation with respect to the king bolt and the locking toggle and operating connection and mechanism therefor.

While I have shown and described my invention as applied to locks for motor controllers and door controllers of street cars, it 40 is, of course, to be understood that my invention is not to be limited or restricted in respect to these purposes as a locking mechanism and a centrifugally operated control therefor is equally well adapted for use in a 45 great many other relations and situations, such, for example, as the locking of the throttle of a steam locomotive to prevent actuation thereof until all the doors for example on the train have been closed, thus securing 50 greater safety of operation of railway trains and preventing accidents occurring through untimely or prematurely starting of the car or train.

The pendulum weight 48 suspended upon 55 the head 45 of the pin 44 permits me to eliminate the usual commutator ring structure employed in like situations while at the same time permitting rotation of the shaft 15 and of the circuit breaker device without inter-

ferring with the terminal connection of the 60 circuit conductor.

Variations and changes in the details of structure will readily occur to persons skilled in the art and still fall within the spirit and scope of my invention. I do not desire therefore to be limited or restricted to the exact details shown and described but I have set forth the objects and the nature of my invention and a construction embodying the principles thereof. What I claim is new and 70 useful and of my own invention and desire to secure by Letters Patent is:—

1. In a car having a driving motor therefor, the combination with a car door, and means for opening and closing the same, of an electrically operated locking device for locking said means against operation, a circuit for said device including a source of current, said locking device being released when current is supplied thereto, a normally open 75 switch included in said circuit, a magnet for controlling said switch whereby when said magnet is energized said switch is closed, and means on the motor shaft actuated by the motor coming to a full stop for energizing said magnet to thereby render operative said locking device.

2. In a car having a driving motor, the combination with a car door and means for opening and closing the same, of an electrically operated locking device for locking said means against operation, a circuit for said device including a source of current, said locking device being released when current is supplied thereto, a normally open switch 80 included in said circuit, a magnet for controlling said switch whereby when said magnet is energized said switch is closed, a centrifugally actuated circuit breaker attached to the motor controlled by the movement of said motor for controlling said magnet whereby when said centrifugal circuit breaker is at rest said magnet is energized.

3. In an electrically operated car, the combination with a car door, means for opening and closing the same, said means being operable only when the car is stationary, a motor controller for controlling the operation of the car, and electrical means for locking and retaining locked said motor controller when 100 said door is open and the car is at rest, said locking means being energized through a circuit completed by a switch closed by the door when in open position.

In testimony whereof I have hereunto set 115 my hand on this 18th day of August, A. D. 1919.

GEORGE WASHINGTON MEYERS.
